HAIR CURLER

Isaac Meohas, Long Beach, Calif.

Application November 23, 1946, Serial No. 712,024

7 Claims. (Cl. 132—41)

1

This invention relates to barrettes, hair-retainers or hair curlers consisting of three limbs between which hair can be gripped and curled.

The barrettes, hair-retainers or hair curlers now in use and disclosed in the prior art usually consist of two limbs joined at one end by some suitable one-way hinge which will allow the hair curler to be opened in one direction only in order to facilitate the insertion of one limb into the hair and allow the other limb to be closed on the selected portion of hair. The above mentioned hair curlers are provided with a clasp on the end opposite from the hinge end which allows the fastening of the two loose ends of the limbs together, thus causing the limbs to hold the hair in a tight grip before the operation of curling is begun. It is found, however, that such constructions do not always lead to the desired result and the object of the present invention is to provide an improved barrette, hair-retainer or hair curler in which particularly firm gripping of the hair may take place. Another object of this invention is to produce a hair curler which may be inserted in the hair with the minimum amount of effort. Still another object of this invention is to produce a hair-retainer which may be opened or closed not only by the conventional hinge method but also by pivotal means.

According to the present invention, three limbs are provided, the limbs being different and distinct from one another and joined in a manner hereinafter disclosed, the basic limb being a solid piece of plastic, or any other suitable material, with an arc therein to fit the curve or contour of the head, one end of the basic limb having a clamping or fold-over lip thereon, said lip being directed inwardly towards the concaved surface of the basic limb, which is more fully described hereinafter. The end opposite from the fold-over lip on said basic limb is provided with a hinge, and pivot means which will allow said basic limb to move not only up and down, as in the ordinary manner obtained by means of a hinge, but also sideways therefrom, said hinge and pivot means to be more fully described hereinafter. The second limb is also provided with an arc similar to the arc provided for in the basic limb, but said limb being a little shorter than the basic limb and being provided with a two pronged end. The opposite end from the pronged end of the second limb is provided with means so that it can be pivoted and hinged on the pivoting and hinging means disclosed in relation to the basic limb. The third limb is curved to the same degree as the basic and second limbs, but having

2

a length greater than the second limb and equal to the basic limb. Third limb is also provided with a fold-over lip at one end and means at the other end so that it can be pivoted and hinged on the pivoting and hinging means disclosed in relation to the basic limb.

In order that the invention may be clearly understood and readily carried into effect, some constructions in accordance therewith will now be described by way of example with reference to the accompanying drawing in which:

Figure 1 shows a side view of all three limbs.

Figure 2 shows a top view of basic limb and side views of second and third limb when expanded.

Figure 3 shows a side view of the modified straight hair-retainer.

Figure 4 shows a side view of the modified and inverted hair-retainer.

Referring now to the drawing and Figures 1 and 2 in particular, A represents the basic plastic limb. For purposes of this example all parts are designated as plastic, but it is to be understood that this invention is in no way limited to plastic compositions alone. The curve or arc in basic limb A may be of any degree depending on the contour of the person's head whose hair is to be treated, 1 represents clamping lip or fold-over, which is constructed in such a manner that the inside surface of the lip will retain and hold limb B by means of prong 2 in position when desired, as hereinafter described. Furthermore, lip 1 is curved inwardly towards the concaved surface of the basic limb A. The opposite end or hinging end of basic limb A is provided with slot 3 and holes 4 and 5. Positioned in holes 4 and 5 and running through slot 3 is hinge pin 6 which is flanged on the sides of basic limb A, as shown at 7 and 8, so as to secure pin 6 therein.

Positioned on hinge pin 6 by means of hole 9 is pivot pin 10. Pivot pin 10 is positioned on hinge pin 6 in such a manner than pivot pin 10 is capable of pivoting to a certain degree around hinge pin 6. Positioned on pivot pin 10 is a second limb B by means of hole 12. Limb B is positioned on pivot pin 10 in such a manner that it can pivot completely around pivot pin 10 in any direction, furthermore, limb B can pivot to a certain degree around hinge pin 6 thus giving it leeway to operate in the manner of a hinge and also in a circular manner around pivot pin 10. The end of second limb B opposite from its hinged and pivoted end is provided with prongs 2 and 11. Fold-over lip 1 will fit over prong 2 thus securing basic limb A to second limb B. Positioned above

second limb B is third limb C which is positioned on pivot pin 10 by means of hole 14 in the same manner as limb B. Separation of limbs B and C on pivot pin 10 is by means of washer 15. The head of pivot pin 10 is flanged, as shown by 16 so as to insure against any of the limbs being disengaged from said pivot pin. The end opposite from pivoted end of limb C is provided with fold-over lip 17, which is curved inwardly towards the convexed surface of limb C so that it makes a snug contact with the under side of prong 11 on second limb B.

A modification of the above described invention is shown in Figure 3 and is designated herein as the straight limb hair curler. This modification is constructed and operates in the same manner as shown and described in relation to Figures 1 and 2, but is varied in that all three limbs, D, E and F are straight, whereas the limbs above are curved in an arc suitable to fit the contour of a human head.

Another modification of the above described invention is shown in Figure 4 and is designated herein as the inverted hair curler. This modification is constructed and operates in the same manner as shown and described in relation to Figures 1 and 2, but is varied therefrom in that all three limbs, G, H and I are curved in an arc opposite from that shown in relation to Figures 1 and 2, i. e., lip 1a is curved inwardly towards the convexed surface of the basic limb G and lip 17a is curved inwardly towards the concaved surface of limb I.

In carrying the invention into effect third limb C is inserted into the hair and underneath the hair desired to be curled. After the third limb is in proper position, second limb B is swung around on pivot pin 10 so that it is directly on top of third limb C and lip 17 is clamped over prong 11 thus clamping the selected portion of hair between the surfaces of third and second limb. After third and second limb are in proper position they are rolled to a sufficient degree to curl the hair around the two limbs. After the hair has been rolled to a sufficient degree, basic limb A is lowered on hinge pin 6 and swung around on pivot pin 10 so that it is directly on top of second and third limb. Lip 1 on basic limb A is clamped over prong 2 so that it holds second limb securely in position, thus holding the rolled hair in a secured position.

The modified straight limb hair curler, as shown in Figure 3 is operated in the same manner as the hair curler shown in Figures 1 and 2 and described above.

The modified inverted hair curler is operated in the following manner, basic limb G is inserted into the hair and underneath the hair desired to be curled so that the concaved side of said basic limb is adjacent to the head. After basic limb G is in proper position, second limb H is swung around on pivot pin 10 so that it is directly on top of basic limb G and lip 1a is clamped over prong 2 thus clamping the selected portion of hair to be curled between the surfaces of basic and second limb. After the basic and second limb are in proper position they are rolled to a sufficient degree to curl the hair around the two limbs. After the hair has been curled to the desired degree, third limb I is swung around on pivot pin 10 so that it is directly on top of basic and second limb and lip 17a is clamped over prong 11 on limb H, thus holding the rolled hair in a secured position.

The foregoing description of my invention is

not to be taken as limiting but only illustrative thereof since many variations may be made by those skilled in the art without departing from the scope of the following claims.

I claim:

1. A hair curler comprising the combination of three limbs, one of said limbs being curved in the form of an arc with a clamping lip at one end and having hinging and pivoting means at the other end, another limb with an arc similar to the arc in the first mentioned limb and being attached at one end to the above mentioned hinging and pivoting means, a third limb with an arc similar to that of the two above mentioned limbs and also being attached to the hinging and pivoting means above described.

2. A hair curler comprising the combination of three limbs, one of said limbs being curved in the form of an arc with a clamping lip at one end, 20 said clamping lip being curved inwardly towards the concaved surface of said limb, and having hinging and pivoting means at the other end, another limb with an arc similar to the arc in the first mentioned limb and being attached at one end to the above mentioned hinging and pivoting means, 25 a third limb with an arc similar to that of the two above mentioned limbs and also being attached to the hinging and pivoting means above described.

3. A hair curler comprising the combination of three limbs, one of said limbs being curved in the form of an arc with a clamping lip at one end, said clamping lip being curved inwardly towards the concaved surface of said limb and 35 having a hinging pin and pivoting pin at the other end, another limb with an arc similar to the arc in the first mentioned limb and being attached at one end to the above mentioned hinging pin and pivoting pin and having at the 40 opposite end two prongs, a third limb with an arc similar to that of the two above mentioned limbs and also being attached to the hinging pin and pivoting pin at one end and having a clamping lip at the other end.

4. A hair curler comprising the combination of three limbs, one of said limbs being curved to fit the contour of a human head with a clamping lip at one end, said clamping lip being curved inwardly towards the concaved surface of said limb, and having a hinging pin running through the other end of said limb, positioned on said hinging pin a pivot pin, another limb with an arc similar to the arc in the first mentioned limb and being attached at one end to the pivot pin, 50 a third limb with an arc similar to that of the two above mentioned limbs and also being attached to the pivot pin.

5. A hair curler comprising the combination of three limbs, one of said limbs being curved to fit the contour of a human head with a clamping lip at one end, said clamping lip being curved inwardly towards the concaved surface of said limb, said limb having a slot at the other end and having a hinging pin running through said 65 limb and slot, positioned on said hinging pin a pivot pin, another limb with an arc similar to the arc in the first mentioned limb and being attached at one end to the pivot pin, a third limb with an arc similar to that of the two above mentioned limbs and also being attached to the pivot pin.

6. A hair curler comprising the combination of three limbs, one of said limbs being straight with a clamping lip at one end and having a hinging pin and pivoting pin at the other end,

another limb being attached at one end to the above mentioned hinging pin and pivoting pin and having at the opposite end two prongs, a third limb also being attached to the hinging pin and pivoting pin at one end and having a clamping lip at the other end.

7. A hair curler comprising the combination of three limbs, one of said limbs being curved in the form of an arc with a clamping lip at one end, said clamping lip being curved inwardly towards the convex surface of said limb and having a hinging pin and pivoting pin at the other end, another limb with an arc similar to the arc in the first mentioned limb and being attached at one end to the above mentioned hinging pin and pivoting pin and having at the opposite end

5 two prongs, a third limb with an arc similar to that of the two above mentioned limbs and also being attached to the hinging pin and pivoting pin at one end and having a clamping lip at the other end.
